UNITED STATES PATENT OFFICE.

LOUIS STEINBERGER, OF NEW YORK, N. Y.

THIRD-RAIL SUPPORT.

SPECIFICATION forming part of Letters Patent No. 761,553, dated May 31, 1904.

Application filed December 7, 1903. Serial No. 184,084. (No model.)

To all whom it may concern:

Be it known that I, LOUIS STEINBERGER, a citizen of the United States, and a resident of the city of New York, borough of Brooklyn, in the county of Kings and State of New York, have invented a new and Improved Third-Rail Support, of which the following is a full, clear, and exact description.

My invention relates to supports and admits of general use, but is more particularly applicable to supports of a type suitable for use in connection with third rails.

It will be understood that in using third rails in connection with electric lines it is desirable to allow for various motions of the rail member, and especially to allow for temporary disconnection as between the rail-insulator and the supporting member which normally engages the same. It is also highly essential that provision be made for allowing the rail to rock slightly in a lateral direction and also for allowing the rail to rock slightly in a plane coincident with its general length. In other words, it is necessary to provide for a certain amount of flexibility in the rail-section, so as to allow the rail-section to adjust itself under varying conditions, thus insuring a more perfect contact with the trolley-shoe.

Reference is to be had to the accompanying drawings, forming a part of this specification, in which similar characters of reference indicate corresponding parts in all the figures.

Figure 1 is a vertical central section through a third rail and support therefor embodying my invention. Fig. 2 is a fragmentary plan view of the same. Fig. 3 is a side elevation, partly in section, showing the same upon a reduced scale and also showing one of the insulator-supports as moved relatively to a rail. Fig. 4 is a section somewhat similar to Fig. 1, but showing the rail as tilted in a lateral direction. Fig. 5 is a sectional elevation taken at right angles to the view shown in Fig. 4 and showing the support as rocking in the general longitudinal direction of the rail, and Fig. 6 is a fragmentary elevation of the means for adjusting the height of the stem 4 of the support.

The cross-ties are shown at 1, and disposed at intervals thereupon are pedestals 2, pref-

erably made of metal and secured to the cross-ties by means of bolts 3. Secured rigidly to each pedestal is a vertical stem 4, provided with a hemispherical end 4^a and also with an angular shoulder 5 and thread 6 for securing the stem rigidly upon the pedestal. An outer shell 7 and an inner shell 9, made of metal, are connected together by means of a body member 8, of insulating material, disposed therebetween. The inner shell 9 is provided with a thickened portion 10 of the shape shown, which constitutes an anchoring-surface for engaging the insulating-body 8 and frictional surface for the stem 4. The shell 7 is provided with a flat face 11 and with lugs 12, which engage the base 14 of the rail-section 13.

Fig. 1 shows the normal position of the device. If, however, the cross-ties move vertically in relation one to another, as indicated in Fig. 3, so that the insulators shown at the right and the left of the figure are relatively higher than the one shown in the middle of the figure, the stem 4, normally supporting the middle insulator, is slightly lowered, as shown at the center of Fig. 3, thus allowing the stem 4 in the center of the figure to clear itself from the insulator which it normally supports. Practically the same thing occurs if for any reason a portion of the rail-section is raised relatively to another portion. Provision is thus made for the raising or lowering of any number of the stems 4 relatively to each other. Suppose now that because of a bad adjustment of the trolley-shoe or of a swerving of the electrical vehicle it should be necessary for the rail to careen in a lateral direction, the insulator is mounted so as to allow for this movement.

As will be seen in Fig. 4, the inner shell 9 is free to tilt slightly, thereby allowing the rail 13 to assume the position indicated or to rock in either direction or at any angle relatively to the general direction of the rail. In order to still further increase the mobility of the supporting connection, the inner shell 9 may move or careen slightly in a plane coincident with the general length of the rail, as indicated in Fig. 5, and of course this movement may take place in either of the two general directions representing the general di-

rection of the rail. In short, my insulator, consisting of the outer and inner shells, with a body of insulating material connecting the same together rigidly, presents a connection which allows a slight movement in almost any direction and which enables the third rail to careen to any angle and yet form a sufficiently solid and reliable support for all practical purposes.

10 The thickened portion 10 of the inner shell 9 is capable of withstanding considerable wear. It will be noted that the hemispherical shape of the upper end 4^a of the stem, which serves as a support for the insulator, is of proper conformity to retain its shape. In other words, the natural wear upon the surface 4^a is of the character which tends to maintain the rotundity of the surface. The rotund surface of the inner shell being concave and the upper surface of the support or stem 4 being convex enables advantage to be taken of this principle.

15 By means of the angular portion 5 the stem 4 may be unscrewed from the pedestal 2 and for this purpose is revoluble independently of the rail and of the members immediately engaging the same. By partially unscrewing the stem 4 by means of the angular portion 5 the stem may be raised relatively to the pedestal 2, as indicated more particularly in Fig. 6. The arrangement therefore serves as an adjustment in case it is desired to virtually lengthen or shorten the stem. For instance, if one of the cross-ties happens to be a little 20 crooked or from any other reason the rail may be a little too high relatively to the pedestal all that is necessary is to partially unscrew the stem 4, thereby virtually lengthening it and causing the device to fit notwithstanding the fact that the pedestal 2 is slightly out of alignment with the other pedestals.

25 As will be seen from the figures, the thickened portion 10 of the inner shell enables the insulator to resist considerable shocks, due to the pounding of the insulator upon the metal stem 4, and vice versa. As the inner shell 9 is depressed and its upper inner surface is rotund, it follows that the pounding as between the hemispherical portion 4^a of the stem and 30 the inner mating surface of the portion 10 fits each other, so as to lessen the severity of the shocks caused by pounding—that is to say, if the stem 4 suddenly descends and suddenly rises it may not strike quite centrally in the inner shell 10 and may glide, therefore, into position by virtue of the curvature of the hemispherical portion 4^a, so that the shock upon the insulator and the other mechanism is to some extent broken. It may also be 35 noted that the bottom portion of the insulator is much larger and heavier than the top portion thereof, so that the center of gravity of the insulator as a rule lies below the hemispherical portion 4^a of the stem 4. On this account the insulator is held in stable equilib-

rium, and therefore tends to return to its normal position when slightly displaced in practically any direction.

I do not limit myself to the particular form of stem-pedestal or other mechanism shown. 70 Neither do I limit myself to the general arrangement shown.

Having thus described my invention, I claim as new and desire to secure by Letters Patent—

1. A third-rail support, comprising a member provided with a portion for engaging a rail and with a bearing-surface, and a supporting member provided with a bearing-surface loosely engaging said bearing-surface of said member for the purpose of enabling said member to rock relatively to said supporting member. 75

2. A third-rail support, comprising a member provided with a portion to be connected with a rail and with a concave bearing portion, and a member provided with a convex bearing portion engaging said concave bearing portion. 85

3. A third-rail support, comprising a member provided with a flat portion to be connected with a rail, and also provided with a concave portion having a bearing-surface, and a member provided with a convex bearing-surface engaging said concave bearing-surface for the purpose of supporting said first-mentioned member, and also for the purpose of allowing the same to have free movement in divers directions relatively thereto. 95

4. A third-rail support, comprising a member provided with a metallic bearing-surface of concave form, and also provided with a portion to be engaged by a rail, and a stem provided with a bearing-surface and with means whereby said stem may be mounted upon a cross-tie. 100

5. A third-rail support, comprising an outer metallic shell provided with a portion for engaging a rail, a member of insulating material mounted within said outer shell, a metallic member mounted within said body of insulating material and anchored thereto, and a supporting member engaging said last-mentioned metallic member which is free to rock thereupon. 110

6. A third-rail support, comprising an outer shell and an inner shell each provided with anchor-surfaces, a body of insulating material engaging both of said shells and held firmly thereto by aid of said anchor-surfaces, and a member engaging one of said shells and normally supporting the same, the other of said shells being provided with a surface for engaging the rail. 115

7. A third-rail support, comprising an outer shell and an inner shell each provided with an anchor-surface, a body of insulating material engaging said shells and held firmly thereto by aid of said anchor-surfaces, and a member engaging one of said shells for supporting the same, the other of said shells being provided 120

with means whereby it may be rigidly secured to a rail-section.

8. A third-rail support, comprising an outer metallic shell provided with a surface for engaging a rail, and an inner metallic shell provided with a thickened portion having a bearing-surface, a body of insulating material engaging said shells, and a supporting member provided with a bearing-surface engaging said bearing-surface of said thickened portion of said inner shell.

9. A third-rail support, comprising a member provided with a flat surface for engaging a rail and with lugs for securing said rail upon said flat surface, and a stem for supporting said member, said member being provided with a portion engaging said stem and free to rock relatively thereto.

10. A third-rail support, comprising a member provided with a portion to be secured to a rail, and also provided with an aperture, and a supporting member engaging said aperture, said member being movable in divers directions relatively to said supporting member.

11. A third-rail support, comprising an outer shell, an inner shell, a body of insulating material disposed intermediate of said shell and connecting the same together so as to form a single member, a rail secured to said member, and supporting mechanism provided with a bearing portion engaging said inner shell, and movable relatively thereto.

12. A third-rail support, comprising a pedestal, a stem detachably connected therewith and provided with a bearing-surface, and a member mounted upon said stem and provided with a surface for loosely engaging the same, so as to allow of relative operative movement therebetween, said member being further provided with means whereby it may be secured upon a rail-section.

13. A third-rail support, comprising an outer shell provided upon its top with a portion for engaging a rail, and also provided internally with an annular bead, a body of insulating material disposed within said outer shell and engaging said bead, and an inner shell embedded within said body of insulating material and provided with a bearing-surface for engaging a support, said bearing-surface being free to move operatively in relation to said support.

14. A third-rail support, comprising a vertically-disposed member, and a member loosely mounted thereon and free to careen relatively thereto, said member being provided with means whereby it may be secured to a rail-section.

15. A third-rail support, comprising a vertically-disposed supporting member provided at its end with a bearing-surface, and a member detachably mounted thereupon and free to rock at different angles thereto, said member being provided with a bearing-surface engaging said bearing-surface of said support.

ing member, and further provided with a surface for engaging a rail-section.

16. A third-rail support, comprising a supporting member, and a member detachably mounted thereon and provided with a portion 70 for engaging a rail, said member being free to careen in the general direction of the length of said rail-section.

17. A third-rail support, comprising a vertically-supporting member, and a member detachably mounted thereon and provided with means for engaging a rail-section, said member being free to rock in a lateral direction crossing the general length of said rail-section.

18. A third-rail support, comprising a vertically-supporting member provided at its upper end with a bearing-surface, and a detachable member loosely mounted upon said supporting member and free to careen slightly 80 in any direction relatively thereto, said member being provided with means for engaging a rail-section.

19. A third-rail support, comprising a vertically-supporting member provided at its upper end with a rotund bearing-surface, and a hollow member mounted thereupon and provided internally with a bearing-surface mating said bearing-surface of said supporting member, said hollow member being further provided with means for engaging a rail and free to be lifted relatively to said supporting member.

20. A third-rail support, comprising a supporting member provided with a bearing-surface, and a hollow member mounted upon said supporting member and depending therefrom, said hollow member being provided with means for engaging a rail-section, and also provided with a bearing-surface engaging the bearing-surface of said supporting member 105 and being held upon said supporting member by its own weight.

21. A third-rail support, comprising an insulating member connected with a rail, and rigid relatively thereto, and a support disposed below said insulating material and loosely engaged thereby so as to allow an operative movement therebetween while in action.

22. A third-rail insulator, comprising an outer metallic shell and a separate inner metallic shell, a body of insulating material disposed between said shells, and a supporting mechanism provided with a bearing portion detachably engaging said inner shell and allowing the same to rock thereupon.

23. A third-rail support, comprising a pedestal, a stem detachably connected therewith and provided with a bearing-surface, and a member adapted for mounting upon said stem 125 and provided with a bearing-surface for engaging the same, said member being free to rock upon said stem in any direction and provided with means whereby it may be secured upon a rail-section.

24. A rail-support, comprising a vertical member, and a member loosely mounted thereon and free to careen relatively thereto, said last-mentioned member having its center of gravity below the point of support and being provided with a surface for engaging a rail. 5
25. A rail-support, comprising a stem, a member mounted thereon and depending from the top thereof, the center of gravity of said member being disposed below the point of support for the purpose of supporting said member in stable equilibrium, and means for connecting a rail with said member. 10
26. A rail-support, comprising a supporting member, and a member loosely mounted thereon and provided with a portion for engaging a rail, said last-mentioned member and said supporting member being provided with mating bearing-surfaces of such conformity 15 as to break the shock due to pounding of said rail relatively to said supporting member. 20
27. A third-rail support, comprising a supporting member, and a member connected therewith and free to careen relatively thereto, said last-mentioned member being provided with means for connecting the same with a rail-section. 25
28. A third-rail support, comprising a supporting member, and a member to be connected with a rail, said members being provided with blow-resisting surfaces in contact with each other. 30
29. A third-rail support, comprising a supporting member, and a member connected therewith and free to be connected with a rail, said members being provided with bearing-surfaces of suitable conformity to resist the blows as between said bearing-surfaces. 35
30. A rail-support, comprising a member connected with a rail and secured rigidly thereto, a pedestal disposed below said member, and a longitudinal stem engaging said first-mentioned member and said pedestal and adjustable in the general direction of its length 40 relatively to said pedestal when said pedestal is in operative position relatively to said rail. 45
31. A rail-support, comprising a supporting member for engaging a rail, a stem engaging said supporting member, and adjustable relatively thereto when said supporting member is in operative position relatively to said rail and a base engaging said stem. 50
32. A rail-support, comprising a base, a stem connected therewith and adjustable relatively thereto when in operative position relatively to the rail, mechanism engaging said stem for the purpose of supporting a rail, and means for insulating said mechanism. 55
33. A rail-support, comprising a supporting member provided with a base, and a member provided with means for engaging a rail, said last-mentioned member being movable relatively to said supporting member and normally resting thereupon in stable equilibrium. 60
34. A rail-support, comprising a metallic casing provided with means for supporting a rail, insulating material mounted within said casing, a metallic member engaging said insulating material, and a supporting member adjustable relatively to said metallic member 65 when the same is in operative position relatively to the rail. 70
35. A rail-support, comprising a hollow member provided with means for engaging a rail, and a supporting member loosely engaging said hollow member for sustaining the same in stable equilibrium. 75
36. A rail-support, comprising a member for supporting a rail, a base portion, and a supporting member connected with said base portion and adjustable relatively to both said member and said base portion when all of said parts are in operative position relatively to the rail. 80
- In testimony whereof I have signed my name 85 to this specification in the presence of two subscribing witnesses.
